ALPHEUS G. HAWS, OF BERKELEY, CALIFORNIA

DESIGN FOR A DRINKING FOUNTAIN BUBBLER HEAD

Application filed August 15, 1932. Serial No. 44,606. Term of patent 7 years.

To all whom it may concern:

Be it known that I, ALPHEUS G. HAWS, a citizen of the United States, and a resident of the city of Berkeley, county of Alameda, State of California, have invented a new, original, and ornamental Design for a Drinking Fountain Bubbler Head, of which the following is a specification, reference being had to the accompanying drawing, forming part thereof.

Figure 1 is a side view of the drinking fountain bubbler head with the design of my invention.

Figures 2 and 3 are front and rear views of the drinking fountain bubbler head.

Figure 4 is a plan view of the drinking fountain bubbler head.

I claim:

The ornamental design for a drinking fountain bubbler head substantially as shown.

ALPHEUS G. HAWS.
